UNITED STATES PATENT OFFICE.

WILLIAM M. SCHOLL, OF CHICAGO, ILLINOIS.

STATURE-INCREASER.

1,152,557.

Specification of Letters Patent.

Patented Sept. 7, 1915.

Application filed December 6, 1913. Serial No. 805,131.

To all whom it may concern:

Be it known that I, WILLIAM M. SCHOLL, a citizen of the United States, residing at Chicago, in the county of Cook and State 5 of Illinois, have invented certain new and useful Improvements in Stature-Increasers, of which the following is a specification.

My invention relates to improvements in height elevators and has for one of its objects to provide an advantageously constructed elevator for insertion in a shoe to lift the heel of the foot materially above the normal heel level of the shoe to increase the apparent height of the wearer and at 15 the same time to give adequate support for the arch of the foot.

It is a common disadvantage of devices employed to increase the apparent height of a wearer that the position of the foot 20 due to their use localizes the strains imposed by the person's weight upon the toes and heels in such fashion as to tend to break down the instep arches and to result in malformation of the feet.

25 In the embodiment of my invention I provide means to give apparently increased height and yet afford such effective distribution of the weight as to give greatest comfort to the wearer and least liability to injury of the foot.

30 In the drawing Figure 1 is a side elevation of a structure embodying my invention; Fig. 2 is a longitudinal section thereof; Fig. 3 is a transverse section on line 3—3 of 35 Fig. 1.

40 In the construction shown 5 indicates the "lifter" or heel lifting member proper, composed of cork or other suitable material, shaped in plan to fit within the heel of the shoe and having its upper surface 6 shaped to receive the wearer's heel. The heel elevating member 5 is of such height as to raise the heel a material distance above the normal level of the shoe, so as to give the desired elevation to the wearer.

45 In conjunction with the elevating member, I provide a metal plate member 7 having at its front and rear ends bearing portions for coaction with the interior bottom of the shoe 50 and between said bearing portions highly arched to extend up to the level of the heel elevating member 5. The abruptly inclined portion 8 of the plate in rear of the shank or highest portion thereof is shaped for coaction with the similarly shaped under sur-

face of the elevating member, such coacting surfaces being preferably somewhat curved so that the bearing portion 9 of the plate at the lower edge connects smoothly with the elevating member at the under side thereof. 60 Thus the elevating member has a large upper surface for support of the heel in elevated position and a relatively small bearing portion. The elevating member is suitably connected to the inclined portion 8 of the 65 plate, as by rivet 10, engaging the plate at its lower end at 11 and at its upper end engaging washer 12 which is suitably seated in the body of the elevating member to leave its upper surface substantially level and 70 smooth.

In front of the highest or shank portion, the plate 7 is shaped longitudinally and transversely for conformity with the overlying foot arch, and first rises above and then 75 inclines downwardly below the highest portion of the elevating member to the level of the shoe adjacent the ball of the foot, to conform with the plantar arch surface of the foot, with the foot inclined or in "tip-toe" position. The entire upper surface formed by the elevating member and downwardly inclined plate portion is preferably 80 covered with a piece of leather 15, while the under side of the device is similarly covered 85 with a piece of thin leather 16.

When the lifter is placed in a shoe it fills the space between the rear inclined portion 8 and the rear walls of the shoe, and is held 90 firmly in upright position by contact with a supporting wall upon all sides thereof as well as by the bearing of the plate on the shoe heel. The arch formation of the plate insures strength and provides a bearing 95 point directly beneath the elevating member and a forward bearing point associated with the elevating member through the front inclined plate portion, so that the elevating member and plate may settle somewhat under the weight of the wearer. The device 100 is so arranged that all parts of the foot are properly supported to prevent injury to the arch of the foot incident to its abnormally inclined position.

Having described my invention, what I 105 claim is:

1. In a device of the character described the combination of a heel elevating member for insertion in the heel of a shoe, and an arched plate, arranged to underlie the ball 110

of the foot at its forward end and support the instep of the wearer, the highest portion of the plate lying flush with the forward top edge of the heel elevating member, the portion at the rear thereof being inclined abruptly downwardly and backwardly to underlie the bottom of the heel elevating member.

2. In a device of the character described 10 the combination of a heel elevating member for insertion in the heel of a shoe and an arched plate arranged to support the instep of the wearer, and bearing at its forward end upon the shoe, the highest portion of 15 the plate lying flush with the top of the elevating member, the portion at the rear of the highest portion being inclined abruptly downwardly along the forward face of the heel elevating member and rearwardly to

underlie the bottom of said elevating member.

3. In a device of the character described 20 the combination of a heel elevating member for insertion in the heel of a shoe, and a plate arranged to span the shank of the 25 shoe and adapted to bear at each end upon the shoe and having an arched portion the elevation of which is greater than that of the normal human instep arch, said elevating member being secured upon the upper surface of the plate near the rear end thereof.

In testimony whereof I hereunto set my hand in the presence of two witnesses.

WILLIAM M. SCHIOLL.

In the presence of—

GEO. T. MAX, Jr.,
MARY F. ALLEN:
